(57) **CLAIM**

The ornamental design for a door jamb enforcer plate, as shown and described.

DESCRIPTION

FIG. 1 is a rear perspective view of a door jamb enforcer plate, showing our new design;

FIG. 2 is a rear elevation view thereof;

FIG. 3 is a front elevation view thereof;

FIG. 4 is a right side view thereof;

FIG. 5 left side view thereof;

FIG. 6 is a top plan view thereof;

FIG. 7 is a bottom plan view thereof; and,

FIG. 8 is a left side view of the door jamb enforcer plate of FIG. 5 in an operative configuration in a door jamb.

The broken line showing of part of the door and part of the door frame in FIG. 8 depicts environment that forms no part of the claimed design.

1 Claim, 4 Drawing Sheets
